UNITED STATES PATENT OFFICE.

HENRY GIBSON O'NEILL, OF NEW YORK, N. Y., ASSIGNOR TO CONRAD HUBERT, OF NEW YORK, N. Y.

ENGINE STARTING AND PUMPING APPARATUS.

1,262,691.

Specification of Letters Patent.

Patented Apr. 16, 1918.

Application filed March 18, 1914. Serial No. 825,691.

To all whom it may concern:

Be it known that I, HENRY GIBSON O'NEILL, a citizen of the United States, residing at the borough of Manhattan, city of New York, in **5** the county of New York and State of New York, have invented certain new and useful Improvements in Engine Starting and Pumping Apparatus, of which the following is a specification, reference being had **10** therein to the accompanying drawings, forming part thereof.

My invention relates to pumping apparatus, more particularly to pumping apparatus installed on automobiles or motor cars **15** for supplying compressed air for tire inflation or for other purposes.

Objects of my invention are to combine such a pumping apparatus with an electrical equipment employed for starting an internal **20** combustion engine or for other purposes, and to combine the pumping apparatus and the engine-starting apparatus in a unitary construction which shall be simple and compact, highly effective in all its functions, **25** durable, reliable, accessible, cool in operation, neat and symmetrical in appearance, inexpensive to manufacture and install, and convenient to install. A further object is to produce such a combined apparatus par- **30** ticularly adapted to be applied to automobiles which have been built without provi- **35** sion having been made for its accommoda- **40** tion, and also well adapted to be supplied as equipment on new cars without altera- **45** tion or re-arrangement of any vital or im- **50** portant parts of the car as previously built without such equipment, and to produce such a combined apparatus suitable for in- **55** stallation at the front of the car. Other **60** more particular objects and advantages of my invention will hereinafter appear.

My invention includes a pumping device arranged to be operated through two sets of gearing, one of these being a set of speed- **45** multiplying gearing pertaining to both the electrical apparatus and to the pumping device, and the other being a set of speed-reducing gearing for the pumping device. My invention also includes novel pumping ap- **50** paratus particularly adapted to be and ef- **55** fectively combined with the electrical appa- **60** ratus. My invention further includes a number of features of construction and com- **65** binations of parts, as will appear from the **70** following description.

I shall now describe the combined pumping and electrical apparatus embodying my invention illustrated in the accompanying drawings and shall thereafter point out my invention in claims.

Figure 1 is a vertical longitudinal section, as seen from the front, of the casing of the apparatus with the inclosed mechanism partly in section, but mostly in elevation.

Fig. 2 is a partial horizontal longitudinal **65** section on planes indicated by the line 2—2 of Fig. 1, as viewed from below, the casing being in central section.

Fig. 3 is a section in the plane of Fig. 1 **70** of parts of the mechanism appearing just to the left of the center in Fig. 1.

Fig. 4 is a transverse section on a plane indicated by the line 4—4 of Fig. 1 as viewed from the left.

Fig. 5 is a greatly enlarged vertical lon- **75** gitudinal section, partly in elevation, of the mechanism appearing at the left in Fig. 1.

Fig. 6 is a less enlarged transverse sec- **80** tion on a plane indicated by the line 6—6 of Figs. 1 and 5, as viewed from the right.

Fig. 7 is a similar partial section indicated by the line 7—7.

Fig. 8 is a view similar to Fig. 6 indicated by the line 8—8, as viewed from the left, the pawls being at a slightly different posi- **85** tion than in Fig. 5.

Fig. 9 is an end elevation of two of the co-operative centrifugally-operated clutch disks or plates.

The mechanism of the apparatus is in- **90** closed in a symmetrical casing, shown as made up of a larger or main part 1 having right and left cylindrical shell portions and a central portion connecting the shell por- **95** tions, a rear middle part 2, and end caps 3 and 4; all parts of the casing being rigidly joined to form a strong and rigid combined casing and supporting frame, the end caps 3 and 4 being shown as provided with lugs for bolting to the side frame of an auto- **100** mobile chassis at the front of the engine.

In the present invention the pumping de- **105** vice, an electrical power device and oper- **110** ating mechanism are so combined that parts of the operating mechanism are common to both the pumping device and the electrical device, and of the remaining parts, some belong or pertain particularly to the pumping device and others particularly to the electrical device.

The combined apparatus has a central shaft 5, which may be an integral portion of the engine shaft, or it may be a short shaft coupled to the engine shaft in axial alignment therewith, probably usually the latter, for greater convenience in installing the apparatus. An engine-connected member, shown as a bevel gear 6, is fixed on the forward end of the central shaft 5 and meshes with a bevel pinion 7. The bevel pinion 7 has a permanently locked engagement with a flanged journal sleeve 8, as by means of interengaging teeth or projections, as best appears in Fig. 1. The sleeve 8 is journaled in a bearing 9 in the casing and its flange or disk portion is secured to a gear frame 10, shown as rigidly formed in a single piece, as will appear by comparing Figs. 5 and 6. A hub or boss 11 is secured to the other side of the gear frame 10, being shown in Fig. 5 as having an enlarged or flange portion screwed into the end of the gear frame, and the hub 11 is shown as journaled in a ball bearing in a partition disk 12 in the casing. The flanged sleeve 8, the frame 10 and the hub 11 together form a rigid gearing carrier. The central shaft 5, the bevel gear 6, the bevel pinion 7 and the gearing carrier are all in permanent operative connection with the engine and may be correctly considered as engine-connected parts or engine-connected members, although the centrally located bevel gear 6 will hereinafter be more particularly referred to as an engine-connected member. It will be apparent that, excepting for structural reasons, the bevel pinion 7 and the several rigidly joined parts 8, 10 and 11 of the gearing carrier could all be formed of a single or integral piece.

The bevel pinion 7 is journaled on the armature shaft 13 of a combined electric generator and motor 14, which for simplicity of terminology is hereinafter referred to as a "dynamotor", and which occupies the cylindrical space in the casing appearing at the right in Fig. 1 and which *per se* may be of any suitable construction. The armature shaft 13 extends transverse to the central shaft 5 and is shown as mounted in ball bearings in the end cap 4 at the right in Fig. 1, and in a supporting disk or transverse wall 15 in the casing at the other end of the dynamo-motor 14, and the armature shaft 13 is also journaled in the gear frame 10 of the gearing carrier, as appears in Fig. 5. The set of gearing comprising the bevel gear 6 and the bevel pinion 7 constitutes speed-multiplying gearing from the engine to the dynamo-motor 14 and from the engine to the pumping apparatus, and constitutes speed-reducing gearing from the dynamo-motor 14 to the engine. The ratio of this gearing illustrated in the drawings is three to one when operating as speed-multiplying

gearing, which, of course, becomes one to three when operating as speed-reducing gearing.

The pumping device is arranged to be operated, through manually controlled clutching means, from the hub 11 of the gearing carrier, which, in the pumping operation, is rotated from the engine by means of the bevel gear 6 and bevel pinion 7. The pumping device and speed-reducing gearing therefor are located in the cylindrical space in the casing at the left of the partition 12, as appears in Figs. 1 and 5.

A worm or spiral pinion 16 is arranged in axial alignment with the gearing carrier and bevel pinion 7. At its end adjacent to the gearing carrier the spiral pinion 16 is shown as provided with a bearing, into which a reduced end portion of the gearing carrier hub 11 is received to rotatively support the spiral pinion at that end. The other end of the spiral pinion 16 is reduced to form a journal, which is supported in a bearing carried by a gearing support or frame 17. The spiral pinion or worm 16 engages a spiral gear or worm wheel 18 having slightly reduced concentric end portions journaled in the support 17, and these concentric end portions of the spiral gears 18 carry crank-pins 19. The axis of the spiral gear 18 is transverse to the axis of the spiral pinion 16, and the spiral gear 18 is shown as located below the spiral pinion 16. The worm gearing or spiral gearing illustrated in the drawings effects a speed reduction of one to four in the operation of the pump.

A pair of pump cylinders 20, shown as supported by a bracket piece 21, are arranged obliquely to the axis of the spiral pinion 16, and extend partly above and partly below a horizontal plane coincident with the axis of the worm 16, and are in parallel relation, one at each side of a vertical plane coincident with the axis of the spiral pinion 16. The cylinders 20 contain reciprocative trunk pistons 22, connected to the crank-pins 19 by piston-rods 23, to be reciprocated thereby. The inclined or oblique arrangement of the pump cylinders 20 and the spiral gearing as arranged contribute much to compactness of construction and utilize the available space in the casing to the best advantage. An outlet or education pipe 24 extends to the outside of the casing through a closure plate 25 of the end cap 3 from a valve chamber 26 common to both pump cylinders 20, and the pump valves, not appearing in the drawings, may be of any suitable construction, as is well understood.

Manually controlled and manually operated clutching means are provided for rotatively connecting the spiral pinion 16 with the journal hub 11 of the gearing carrier to

operate the pump from the engine. The journal portion of the hub 11 projects from its bearing and carries a clutch member 27 splined thereon and having inclined clutch 5 teeth adjacent to the worm 16, which is of enlarged diameter at that end and provided with inclined clutch teeth co-operative with those of the clutch member 27. The slideable clutch member 27 is operated by a clutch 10 lever 28 shown as pivoted on the partition disk 12.

A rack guide 29 is secured in the upper part of the casing and guides a rack 30, which is connected to the clutch lever 28 by 15 a rod 31 guided by an abutment head 32 carried by the rack guide 29. A coiled thrust spring 33 surrounds the rod 31 between the abutment 32 and the rack 30 and will shift the clutch member 27 to the disengaged 20 position shown in the drawings and maintain it there. A key 34, the end portion of the stem of which is a small pinion, may be inserted from outside of the casing through a suitable opening therein and into 25 a corresponding opening or key-hole in the rack guide 29, the pinion teeth of the key 34 then engaging the rack 30 (compare Figs. 1 and 5).

By manually rotating and holding the key 30 34, the clutch teeth of the clutch member 27 will be engaged with the clutch teeth of the spiral pinion or worm 16 and the hub 11 of the gearing carrier will be rotatively connected to the spiral pinion 16, so that the 35 latter may be rotated from the former. It will be understood that the pump can now be operated from the engine through the bevel gear 6 and bevel pinion 7, operating as speed-multiplying gearing at 40 the ratio of three to one, and through the spiral pinion 16 and spiral gear 18, operating as speed-reducing gearing at the ratio of one to four, the combined action of the two sets of gearing effecting a speed- 45 reduction from the engine to the pump in the ratio of three to four, or three-fourths to one, which has been found to be a desirable ratio. The small diameter of the high speed intermediary pinions 7 and 16 assists 50 to compactness of the apparatus and also provides for the employment of the spiral or worm gearing for operating the pump, such gearing advantageously combining with the pair of obliquely arranged pump cylinders 55 20, as hereinbefore described. Furthermore, the power-transmitting gearing carrier, the bevel pinion 7 and the bevel gear 6 all form parts of the electrical apparatus as well as of the pump, and all parts of the pumping 60 apparatus and electrical apparatus are effectively combined.

The end portion of the dynamo-motor armature shaft 13 journaled in the gearing frame 10 has teeth thereon forming a small 65 pinion 35 within the gearing carrier which

extends freely into a hollow or cavity in the enlarged portion of the hub 11 of the gearing carrier. The small pinion 35 of the armature shaft 13 meshes with one or more, shown as three, planetary gears 36 mounted, 70 by means of journal pins 37, in the gear frame 10 of the gearing carrier. The planetary gears 36 mesh with an internal gear or internal-toothed ring 38 shown as rigidly secured by means of tap bolts 39 to a shell 75 or gear-inclosing case 40 and to a pawl-carrying locking ring 41. The shell 40 and the locking ring 41 are rotatively mounted or journaled on the gear frame 10 at the right and left, respectively, as appears in Fig. 5. 80 A stationary ratchet ring 42 is fixed on the partition disk 12 and is engaged by pawls 43 pivoted on the locking ring 41 and lightly pressed to engaging position by springs 44 (Fig. 8). The ratchet ring 42 and the pawls 85 43 are arranged to lock or anchor the internal gear ring 38 in the direction of torque corresponding to an engine-starting operation.

In effecting an engine-starting operation, 90 the dynamo-motor 14 is operated as a motor, the direction of rotation of the armature shaft 13 being clockwise as viewed from the left in Figs. 1 and 5, and as indicated by the arrows in several figures of the drawings. 95 In the engine-starting operation, the gear ring 38 will be held stationary by the pawls 43 engaging the stationary ratchet ring 42 and rotation will be imparted to the gearing carrier, including the gear frame 10 and 100 flanged journal sleeve 8, at a greatly reduced rate, the ratio of this reduction in the construction illustrated in the drawings being about one to ten. The flanged sleeve 8 of the gearing carrier being permanently locked 105 to the bevel pinion 7, as hereinbefore described, the engine will be started from the dynamo-motor 14 through the planetary speed-reducing gearing and through the bevel gearing 6-7 operating as speed-reducing 110 gearing, the total speed reduction being at the ratio of about one to thirty, but obviously it could be substantially anything desired.

When the engine starts, its speed accelerates and rotation at an increased rate is imparted to the gearing carrier in the same direction as was its movement in starting the engine. The direction of rotative thrust or torque now being reversed, the pawls 43 115 will release to permit the gear ring 38 and its adjuncts to rotate with the gearing carrier. The clutch member 27 may now be moved into engagement with the clutch teeth of the worm or spiral pinion 16, by means of 120 the manual key 34, to effect the operation of the pump from the engine through the bevel gearing and the spiral gearing, as hereinbefore described.

Means are provided for connecting the 130

gearing carrier directly to the armature shaft 13 to operate the dynamo-motor 14 as a dynamo without the operation of the planetary gearing. The hub 11 of the gearing carrier has the outer portion of its cavity enlarged, so as to provide a shoulder, and within this enlarged portion of the cavity rotatively carries a plurality of sheet metal clutch plates or clutch disks 45 having projections slideable in keyways or grooves within the hub 11 (Figs. 5 and 9). Similar cooperative clutch plates or disks 46 are rotatively carried by the extended end portion of the armature shaft pinion 35, being provided with internal teeth engaging or interlocking with the spur teeth of the pinion 35 (Figs. 5 and 9), so that the plates 46 are slideable longitudinally of the pinion 35. The clutch plates 45 and 46 are arranged in alternate relation, as appears in Fig. 5, and a thrust ring 47 is shown as placed beyond the clutch plates so that all of the clutch plates 45 and 46 will be between this thrust ring and the shoulder of the hub 11 at the bottom of the enlarged portion of its cavity. Thrust pins 48, shown as three in number, guided in the gearing frame 10, are operated by a corresponding number of centrifugal weights 49 pivoted in the gear frame 10, to clamp together the clutch plates 45 and 46 and lock or rotatively connect the hub 11 of the gearing carrier to the pinion 35 of the armature shaft 13, so that, through readily traceable connections hereinbefore described, the armature shaft 13 will be rotated by the engine at the speed of the bevel pinion 7 and without the operation of the planetary gearing, the gear ring 38 and connected parts now rotating idly with the gearing carrier.

Under self-actuation of the engine, the rotative speed of the gearing carrier is sufficient to cause a firm gripping and frictional locking of the clutch plates 45 and 46, by reason of the centrifugal force developed in the weights 49; but at the much lower rotative speed of the gearing carrier in the engine-starting operation no such gripping action is developed and the clutch plates 45 and 46 may relatively rotate, the gear ring 38 then being locked against rotation by the pawls 43, as hereinbefore described. Also it should be noted that when the gearing carrier is rotated in the operation of the dynamo-motor 14 as a dynamo, the pawls 43 will be thrown clear of the ratchet teeth of the ratchet ring 42 by centrifugal force, so that there will be no clicking of these pawls on the ratchet teeth. It is to be observed that the dynamo-motor 14 will be operated as a dynamo from the engine through the bevel gearing 6-7 operating as speed-multiplying gearing at the ratio of three to one, and without the operation of the planetary gearing, the several

parts of which now rotate together without relative movement.

When the dynamo-motor 14 is operated as a dynamo, the electrical energy generated is stored and utilized to operate the dynamo-motor as a motor in the engine-starting operation. Also it is to be understood, in accordance with common practice, that such electrical energy, either stored or taken directly from the dynamo motor 14 operated as a dynamo, may be used for other than engine-starting operations. Any suitable regulating, controlling and indicating devices or instruments may be included in the electrical equipment, as is well understood in the art.

Obviously the construction permits the dynamo-motor to be used as a power device for driving the pump and this could be accomplished without serious added power consumption arising from the engine connection by permitting the engine to run idly with the pet cocks of its cylinders open to relieve compression.

Means are provided for manually starting the engine in the usual way in case any of the parts of the apparatus concerned in the engine-starting operation should get out of order. The bevel gear 6, back of its bevel teeth, is provided also with spur teeth, forming a spur gear in one piece with the bevel gear. Another spur gear 50 meshes with the spur teeth of the gear 6 and is fixed on a short shaft 51 journaled in the casing and which projects forward to the outside of the casing below the armature shaft 13, for the application of a usual crank.

It is to be noted that the weight of the combined pumping and electrical apparatus is substantially the same at each side of the central shaft 5, and that the apparatus is of symmetrical appearance. The arrangement of the pumping device with its set of speed-reducing gearing and the set of planetary speed-reducing gearing employed in starting the engine, at one side of the central shaft 5 and the dynamo-motor 14 at the other side of the shaft 5, with the set of gearing common to the dynamo-motor and to the pumping device placed at a middle position, is involved in the effective combination of the several parts of the unitary apparatus.

It is obvious that various modifications may be made in the construction shown in the drawings and above particularly described within the principle and scope of my invention.

I claim:

1. A combined apparatus including a pumping device, such apparatus comprising, in combination, a high speed device, a set of speed-multiplying gearing for operating the high speed device, a pumping device, and a set of speed-reducing gearing

- for the pumping device operated by said set of speed-multiplying gearing, whereby the high-speed device will be operated at one rate of speed through the set of speed-multiplying gearing and the pumping device will be operated at a resultant differential rate of speed through both said sets of gearing.
2. A combined apparatus including a pumping device, comprising, in combination, a high speed device, a set of speed-multiplying gearing therefor, a pumping device, and a set of speed-reducing gearing therefor operated by the multiplying gearing of the high speed device and having a greater ratio of reduction than the ratio of multiplication of the speed-multiplying gearing of the high speed device, so that the two sets of gearing combined effect a reduction in speed for the pumping device.
3. A combined electrical and pumping apparatus comprising, in combination, an electric generator, driving means therefor including a set of speed-multiplying gearing, a pumping device, and a set of speed-reducing gearing therefor operated by the speed-multiplying gearing of the generator so that the generator will be operated at one speed ratio through one of the sets of gearing and the pumping device will be operated at a different speed ratio through both sets of gearing.
4. A combined electrical and pumping apparatus comprising, in combination, an electric generator, driving means therefor including a set of speed-multiplying gearing, a pumping device, and a set of speed-reducing gearing therefor operated by the speed-multiplying gearing of the generator and having a greater ratio of speed reduction than the ratio of speed multiplication of the speed-multiplying gearing of the generator so that the generator will be operated at a multiplied speed ratio through one of the sets of gearing and the pumping device will be operated at a reduced speed ratio through both of the sets of gearing.
5. A combined electrical and pumping apparatus comprising, in combination, a pumping device, two sets of gearing for operating the pumping device, one of which is a set of speed-multiplying gearing and the other of which is a set of speed-reducing gearing so that the pumping device will be operated at the resultant differential ratio produced by the two sets of gearing, and a dynamo-motor operable as a dynamo by means of the set of speed-multiplying gearing and operable as a motor for operating the pumping device through the set of speed-reducing gearing, whereby the dynamo-motor may be operated as a dynamo through the set of speed-multiplying gearing and the pumping device may be differentially operated through both sets of gear-
- ing, or the pumping device may be operated from the dynamo-motor operating as a motor through the set of speed-reducing gearing only.
6. A combined electrical and pumping apparatus comprising, in combination, a pumping device, two sets of gearing for operating the pumping device, one of which is a set of speed-multiplying gearing and the other of which is a set of speed-reducing gearing having a greater ratio of speed reduction than the ratio of speed multiplication of the speed-multiplying gearing so that the pumping device will be operated at a reduced speed ratio by reason of the combined action of both the sets of gearing, and a dynamo-motor operable as a dynamo by means of the set of speed-multiplying gearing and operable as a motor for operating the pumping device through the set of speed-reducing gearing, whereby the dynamo-motor may be operated as a dynamo through the set of speed-multiplying gearing and the pumping device may be differentially operated at a reduced rate through both said sets of gearing, or the pumping device may be operated through the set of speed-reducing gearing only from the dynamo-motor operating as a motor.
7. A combined electrical and pumping apparatus comprising, in combination, a pumping device, two sets of gearing for operating the pumping device, power-transmitting connections between the two sets of gearing including manually controlled clutching means for connecting together the two sets of gearing to operate the pumping device through both sets of gearing, and a dynamo-motor operable as a dynamo by means of one of said sets of gearing and operable as a motor for operating the pumping device through the clutching means and the other said set of gearing, whereby the dynamo-motor may be operated as a dynamo through one of the sets of gearing either with or without the concurrent operation of the pumping device through both sets of gearing, or the pumping device may be operated through only one of the sets of gearing from the dynamo-motor operating as a motor.
8. A combined electrical and pumping apparatus comprising, in combination, a pumping device, two sets of gearing for operating the pumping device, one of which is a set of speed-multiplying gearing and the other of which is a set of speed-reducing gearing, power-transmitting connections between the two sets of gearing including manually controlled clutching means for connecting together the two sets of gearing to operate the pumping device through both sets of gearing, and a dynamo-motor operable as a dynamo by means of the set of speed-multiplying gearing and operable as

6 a motor for operating the pumping device through the clutching means and the set of speed-reducing gearing, whereby the dynamo-motor may be operated as a dynamo through the set of speed-multiplying gearing either with or without the concurrent operation of the pump, or the pumping device may be operated through only the set of speed-reducing gearing from the dynamo-motor operating as a motor.

10 9. A combined electrical and pumping apparatus comprising, in combination, a pumping device, means for operating the pumping device including a set of speed-multiplying gearing, a set of speed-reducing gearing between the speed-multiplying gearing and the pumping device, clutching means for connecting together the two sets of gearing, and a dynamo-motor operable as a dynamo by means of the set of speed-multiplying gearing and operable as a motor for operating the pumping device through the clutching means and the set of speed-reducing gearing.

15 10. A combined electrical and pumping apparatus comprising, in combination, a pumping device, means for operating the pumping device including a set of speed-multiplying gearing, a set of speed-reducing gearing between the speed-multiplying gearing and the pumping device and having a greater ratio of speed reduction than the ratio of speed multiplication of the speed-multiplying gearing, power-transmitting connections between the two sets of gearing including manually controlled clutching means for connecting together the two sets of gearing to operate the pumping device at a reduced speed ratio through both the sets of gearing, and a dynamo-motor operable as a dynamo by means of the set of speed-multiplying gearing and operable as a motor for operating the pumping device through the clutching means and the set of speed-reducing gearing.

20 11. A combined electrical and pumping apparatus comprising, in combination, a gear, a pinion driven from the gear having its axis transverse to the axis of the gear, a second pinion in axial alignment with the first, driving connections between the pinions, a gear driven by the second pinion having its axis transverse to the axis of said second pinion, a pumping device operated by the latter gear, and a dynamo-motor connected to the first pinion, whereby the dynamo-motor may be operated from the first pinion as a dynamo or may operate as a motor to drive the pumping device from the second pinion.

25 12. A combined electrical and pumping apparatus, comprising, in combination, a gear, a pinion meshing with the gear having its axis transverse to the axis of the gear, a second pinion in axial alignment with the

first, a gear driven by the second pinion having its axis transverse to the axis of said second pinion, a pumping device operated by the latter gear, power-transmitting connections between the pinions including manually controlled clutching means, and a dynamo-motor connected to the first pinion to be driven thereby as a dynamo and adapted to drive the second pinion and the pumping device through said clutching means when operating as a motor.

30 13. In a combined pumping apparatus and electrical equipment for engine-propelled vehicles, the combination of an electric generator, means for operating the generator from the engine including an engine-connected gear and a pinion engaged by the gear, a pumping device, speed reducing gearing therefor, and power-transmitting connections for connecting said pinion to the speed-reducing gearing of the pumping device for operating the pumping device from the engine through such connections, such connections including manually controlled clutching means.

35 14. In a combined pumping apparatus and electrical equipment for vehicles propelled by internal combustion engines, the combination of a dynamo-motor, a set of gearing operative as speed-reducing gearing from the dynamo-motor to the engine and as speed-multiplying gearing from the engine to the dynamo-motor, a second set of gearing constituting speed-reducing gearing connecting the dynamo-motor to the first set of gearing and providing for the operation of the dynamo-motor as a motor to start the engine through both sets of gearing operating as speed-reducing gearing, automatically acting clutching means for discontinuing the operation of the second set of gearing and connecting the first set of gearing with the dynamo-motor to operate the dynamo-motor as a dynamo without the operation of the second set of gearing and with the first set of gearing operating as speed-multiplying gearing, a pumping device, speed-reducing gearing therefor, and manually controlled clutching means for connecting the speed-reducing gearing of the pumping device with the first set of gearing for operating the pumping device from the engine through the first set of gearing operating as speed-multiplying and also through the speed-reducing gearing belonging to the pumping device so that the pumping device will be operated at the differential rate produced by the combined action of these two sets of gearing.

40 15. In a combined pumping apparatus and electrical equipment for vehicles propelled by internal combustion engines, the combination of an engine-starting electric motor, a set of gearing operative as speed-reducing gearing for the motor, a pumping device,

- and a set of speed-reducing gearing for the pumping device operated by the set of gearing of the motor operating as speed-multiplying gearing from the engine so that the pumping device will be operated through both sets of gearing, one of which operates as speed-multiplying gearing and the other of which operates as speed-reducing gearing.
16. In a combined pumping apparatus and electrical equipment for vehicles propelled by internal combustion engines, the combination of an engine-starting electric motor, operating connections between the motor and the engine including gearing operative as speed-reducing gearing from the motor to the engine, a pumping device, speed-reducing gearing therefor, and power-transmitting connections connecting the speed-reducing gearing of the pumping device with the gearing of the motor so that the pumping device will be operated through its speed-reducing gearing and through the gearing of the motor operated as speed-multiplying gearing from the engine, such power-transmitting connections including manually controlled clutching means.
17. In a combined pumping apparatus and electrical equipment for engine-propelled vehicles, the combination of an electrical device, an engine-connected gear rotative at engine speed, a pinion permanently engaged by the gear and operatively connected to the electrical device, a pumping device, speed-reducing gearing therefor, and operating connections for connecting said pinion with the speed-reducing gearing of the pumping device for operating the pumping device from the engine through such connections, such operating connections including manually controlled clutching means.
18. In a combined pumping and electrical apparatus for engine-propelled vehicles, the combination of an engine-connected gear in alignment with the engine shaft, an electrical device at one side of such gear and engine shaft, a pumping device and speed-reducing gearing therefor at the other side of such gear and engine shaft, a pinion engaged by the gear and operatively connected to the electrical device, and operating connections including manually controlled clutching means for connecting said pinion with the speed-reducing gearing of the pumping device.
19. In a combined pumping and electrical apparatus for engine-propelled vehicles, the combination of an engine-connected member, an electrical device at one side of such member, a pumping device and a set of gearing therefor at the other side of such member, power-transmitting connections permanently connecting the engine-connected member and the electrical device, and operating connections including manually controlled clutching means for connecting the gearing of the pumping device with the engine-connected member to operate the pumping device from the engine.
20. In a combined pumping and electrical apparatus for engine-propelled vehicles, the combination of an engine-connected member, an electrical device at one side of the engine-connected member, a pumping device at the other side of the engine-connected member, power-transmitting connections permanently connecting the engine-connected member and the electrical device, and operating connections including manually controlled clutching means for connecting the pumping device with the engine-connected member to operate the pumping device from the engine.
21. In a combined pumping and electrical apparatus for vehicles propelled by internal combustion engines, the combination of an engine-connected member, a dynamo-motor at one side of the engine-connected member, a pumping device and speed-reducing gearing therefor at the other side of the engine-connected member, a set of speed-reducing gearing at the same side of the engine-connected member as the pumping device and connected with the engine-connected member and with the dynamo-motor to effect an engine-starting operation through this set of speed-reducing gearing from the dynamo-motor operated as a motor, automatically acting clutching means for connecting the engine-connected member with the dynamo-motor and discontinuing the operation of the set of speed-reducing gearing to operate the dynamo-motor as a dynamo without the operation of the set of speed-reducing gearing, and manually controlled clutching means for connecting the speed-reducing gearing of the pumping device with the engine-connected member to operate the pumping device in conjunction with the operation of the dynamo-motor as a dynamo when so desired.
22. In a combined pumping and electrical apparatus, the combination of a dynamo-motor, a pumping device, a set of gearing common to the dynamo-motor and to the pumping device operative as speed-multiplying gearing for the pumping device and for the dynamo-motor operated as a dynamo and operative as speed-reducing gearing for the dynamo-motor operated as a motor, and a set of speed-reducing gearing for the pumping device.
23. In a combined pumping and electrical apparatus, the combination of a dynamo-motor, a pumping device, a set of gearing common to the dynamo-motor and to the pumping device operative as speed-multiplying gearing for the pumping device and for the dynamo-motor operated as a dynamo and operative as speed-reducing gear-

ing for the dynamo-motor operated as a motor, a set of speed-reducing gearing for the pumping device, and another set of speed-reducing gearing for the dynamo-motor operated as a motor.

24. In a combined pumping and electrical apparatus, the combination of an electrical device, a pumping device, and a set of gearing common to both the electrical device and the pumping device, such gearing being operative as speed-multiplying gearing for the pumping device.

25. In a combined pumping apparatus and electrical equipment for engine-propelled vehicles, the combination of an electrical generator, means for operating the generator from the engine, such means including an engine-connected gear and a pinion engaged by the gear, a pumping device, and power-transmitting connections for connecting said pinion to the pumping device for operating the pumping device from the engine through such connections, such connections including manually controlled clutching means.

26. In a combined pumping apparatus and electrical equipment for engine-propelled vehicles, the combination of an electrical device, an engine-connected gear rotative at engine speed, a pinion permanently engaged by the gear and operatively con-

nected to the electrical device, a pumping device, and operating connections for connecting said pinion with the pumping device for operating the pumping device from the engine through such connections, such operating connections including manually controlled clutching means.

27. In a combined pumping apparatus and electrical equipment for vehicles propelled by internal combustion engines, the combination of a dynamo-motor, power-transmitting connections between the dynamo-motor and the engine including automatically acting clutching means and gearing for operating the dynamo-motor as a dynamo from the engine at one speed ratio and for starting the engine from the dynamo-motor operated as a motor at another speed ratio, a pumping device, speed-reducing gearing therefor, and operating connections including manually controlled clutching means for connecting the dynamo-motor with the speed-reducing gearing of the pumping device for operating the pump from the dynamo-motor operated as a motor.

In testimony whereof I have affixed my signature in presence of two witnesses.

HENRY GIBSON O'NEILL.
